Attorney

UNITED STATES PATENT OFFICE.

ROBERT S. BLAIR, OF SOUND BEACH, CONNECTICUT.

ASH RECEIVER.

Application filed April 27, 1917. Serial No. 164,993.

This invention relates to ash receivers or trays and mountings therefor.

One of the objects of the present invention is to provide a relatively inexpensive 5 ash receiver or ash tray of simple and practical construction. Another object is to provide a compactly-disposed device of the above general character which may be conveniently used. Another object is to provide 10 a device of the above character which may be quickly emptied without removal from its support. A further object is to provide an ash tray with means for quickly and thoroughly removing the ashes from cigars 15 or cigarettes without injury to the wrapper as the ashes are removed.

Other objects will be in part obvious from the annexed drawings and in part indicated in connection therewith by the following 20 analysis of this invention.

This invention accordingly consists in the features of construction, combination of parts and in the unique relations of the members and in the relative proportioning 25 and disposition thereof; all as more completely outlined herein.

To enable others skilled in the art so fully to comprehend the underlying features thereof that they may embody the same by 30 the numerous modifications in structure and relation contemplated by this invention, drawings depicting a preferred form have been annexed as an illustrative embodiment as a part of this disclosure, and in such 35 drawings like characters of reference denote corresponding parts throughout all the views, in which

Fig. 1 is a perspective view of the complete device in operative position;

Fig. 2 is a longitudinal sectional elevational view thereof;

Fig. 3 is a detail sectional plan view.

Referring now to the drawings in detail, 5 represents the arm of a chair supported from uprights 6 and carrying upon its under side a movable ash tray, as shown. This tray comprises a concaved body portion 7, preferably formed of sheet metal, and provided with an extension 8 at one end pivotally connected and supported by a bolt or 10 stud 10. The device is held in place by means of a removable wing nut 11, although other forms of attaching means may be used, if desired, for preventing unauthorized removal.

Adjacent the stud 10 is a pin 12 adapted to travel in a slot or cut away portion 13 at the end of the extension 8, thereby to limit the rotative movement of the ash tray about the bolt 10. The slot 13 which may be varied in length as desired, will, as herein illustrated, permit the ash tray to swing inwardly to a position underneath and parallel with the arm 5 or swing in the opposite direction to a position directly at right angles thereto.

The ash tray is preferably composed of sheet metal stamped into the desired shape, although it is, of course, to be understood that other materials may be used, if desired. 70 The body portion 7 is provided with downwardly directed side wings 14 forming a funnel or guide, and having a central depressed opening 15 adapted to guide the end of a cigar with its ashes into the interior of the body member 7. An integral cigar rest 16 is also provided at one or more points about the rim.

In order to empty the ash tray, the body portion 7 has a central opening on its under side into which a stopper member or cork 17 is adapted to be inserted. Surrounding this cork is an upwardly projecting flange 18 forming a cup and centrally mounted therewithin is a compression spiral or helical 85 funnel-shaped spring 20. This spring, which is immediately below the opening 15, is adapted to be engaged by the burning end of the cigar and on depression, remove the ashes from the end thereof by a relative 90 grinding motion. The spring, of course, is of very light wire and will easily remove the ashes without injury to the wrapper of the cigar, and swing to accommodate itself to an uneven burning end.

It is believed that the method of use and operation of a device of this character is obvious from the above, and a description thereof is unnecessary. It will be seen that the device may be easily and quickly applied to the under side of any chair arm, table or other article of furniture, as desired, and swung out to the position shown in Fig. 1, when in use. A removal of the stopper 17 will allow the cleaning of the ash tray without removal of the complete device from the chair arm, although at any time when so desired, or found necessary, the entire device may be removed and washed. It is therefore believed that the present invention 110

which is of simple and practical construction and inexpensive to manufacture, is adapted to accomplish, among others, all of the objects and advantages herein set forth.

5 I realize that considerable variation is possible in the details of construction and arrangement of parts without departing from the spirit of my invention, and I therefore do not intend to limit myself to the specific 10 form shown and described.

I claim:

1. In construction for ash trays, in combination, an ash-receiving portion, substantially stationary supporting means, 15 means adapted to mount said ash-receiving portion on said supporting means, said ash-receiving portion being provided with an opening at the bottom and being shaped to discharge its contents toward said opening, 20 and a removable plug fitted in and adapted to close said opening.

2. In construction for ash trays, in combination, an ash-receiving portion, substantially stationary supporting means, means 25 adapted to mount said ash-receiving portion on said supporting means, said ash-receiving portion being provided with an opening at the bottom and being shaped to discharge its contents toward said 30 opening, and a removable plug fitted in and adapted to close said opening, said mounting means being formed to permit said ash-receiving portion to swing under said supporting means.

3. In combination, an ash-removing device comprising a yielding member adapted yieldingly to engage and substantially to conform to the burning surface of the end 40 of a cigar and remove the ashes therefrom, said member being constituted to permit the ashes to pass therethrough and means adapted to support said yielding member in position for use.

4. In a device of the class described, in combination, a resilient device adapted yieldingly to engage the end of a cigar and comprising a yielding coiled spring extending across the path of the cigar which is adapted to conform to the burning surface thereof 50 and a receptacle positioned to receive ashes removed by said spring.

5. A device for receiving ashes comprising a receptacle, yielding means above the bottom of said receptacle adapted to engage the 55 end of a cigar and remove the ashes therefrom, and guiding means adapted to guide a cigar toward the same, said first means being adapted to accommodate itself to the uneven burning end of the cigar.

6. A receptacle for ashes, an ash-removing device mounted over the bottom of said receptacle, and adapted to discharge ashes thereinto and guiding means mounted above the bottom of said receptacle having opposite walls converging toward said device

and adapted to coact upon a cigar to guide the end thereof into operative relation with said ash-removing device.

7. In combination, an ash-removing device comprising a yielding member adapted 70 yieldingly to engage the burning surface of the end of a cigar, and means converging toward said device and adapted to guide the end of the cigar into operative relation thereto.

8. An ash receiving receptacle and a yielding device mounted in said receptacle adapted yieldingly to engage the end of a cigar and remove the ashes therefrom, the sides of said receptacle converging toward and 80 adapted to guide the end of a cigar towards said yielding device.

9. In combination, a supporting device adapted to be mounted upon a fixed member, ash-removing means adapted to be engaged by and break up the ash of a cigar and formed to permit the broken ash to pass therethrough, a receptacle connected with said supporting device and positioned to receive the ash from said ash-removing means, 90 and guiding means having converging walls adapted to coact upon a cigar to guide the end thereof toward and into engagement with said ash-removing means, said receptacle being removable with respect to said 95 supporting device.

10. In combination, a supporting device adapted to be mounted upon a fixed member, yielding ash-removing means adapted to be engaged by and accommodate itself to the 100 burning surface of a cigar and break up the ash thereon and permit the same to pass therethrough, a receptacle connected with said supporting device and positioned to receive the ash broken by said ash-removing 105 means, and guiding means adapted to guide the end of a cigar toward and into engagement with said ash-removing means, said receptacle being removable with respect to 110 said supporting device.

11. In combination, a supporting device adapted to be mounted on a fixed member, yielding ash-removing means adapted to be engaged by and yieldingly accommodate itself to the burning surface of a cigar and break up the ash thereon, a receptacle connected with said supporting device and positioned to receive ash from said ash-removing means, and guiding means adapted to 115 guide the end of a cigar toward and into engagement with said ash-removing means.

12. In combination, a supporting device adapted to be mounted on a fixed member, ash-removing means adapted to be engaged by and break up the ash on a cigar and permit 120 the same to pass therethrough, a receptacle connected with said supporting device and positioned to receive the ash from said ash-removing means, said receptacle having an 125 opening in its bottom, a removable device 130

adapted to close said opening, and guiding means adapted to guide the end of a cigar toward and into engagement with said ash-removing means.

5 13. In combination, an ash-removing device adapted to substantially fit the burning surface of a cigar and provided with apertures for the broken ash to pass therethrough, said device extending across the burning end of the cigar, a supporting 10 means adapted to mount said device in position for use, and guiding means adapted to engage and guide the end of a cigar toward and into engagement with said ash removing device. 15

In testimony whereof I affix my signature.

ROBERT S. BLAIR.
